CLAIM

The ornamental design for a flag for tag-type game, as shown and described.

DESCRIPTION

FIG. 1 is a top plan view of a flag for tag-type game showing my new design;

FIG. 2 is a front elevational view thereof;

FIG. 3 is a right side elevational view thereof;

FIG. 4 is a left side elevational view thereof;

FIG. 5 is a back elevational view thereof;

FIG. 6 is a bottom plan view thereof; and,

FIG. 7 is an enlarged cross-sectional view taken along line 7—7 of FIG. 2 to show surface contour thereof.

FIG. 1.FIG. 4.*FIG. 2.*FIG. 3.*FIG. 5.

FIG. 6.FIG. 7.
